METHOD AND APPARATUS FOR WELL OPERATIONS EMPLOYING HYDROGEN PEROXIDE

Paul G. Carpenter, Bartlesville, Okla., assignor to Phillips Petroleum Company, a corporation of Delaware

Application January 4, 1949, Serial No. 69,213

17 Claims. (Cl. 166—1)

1

This invention relates to processes and apparatus for removing solid materials from a portion of a wall of a well by concentrated hydrogen peroxide and/or its decomposition products. In one specific aspect it relates to cutting off a pipe in a well. In another specific aspect it relates to perforating holes in a pipe in a well. In another specific aspect it relates to cleaning the surface of a well bore by removing mud or encrustations or deposits. In another specific aspect it relates to drilling a well bore.

In carrying out any process involving the removal of solid material from a portion of a wall of a well, difficulties are experienced in the prior art in supplying a sufficient amount of power at a point deep in the earth inside the small confines of a bore hole. Most sources of power require combustion pipes or cables to supply the power and require removal of the products of combustion or have other disadvantages of an obvious nature. Operating at the bottom of a small diameter hole aggravates all problems that would occur at the surface of the ground.

I have found that by employing concentrated hydrogen peroxide as a source of power and releasing this power by a suitable hydrogen peroxide decomposition catalyst that I can produce a powerful jet of steam and oxygen which is capable of cutting pipe in two, perforating holes in the pipe, cleaning the wall of the well and drilling the well to a greater depth. In practicing this process I make use of the simple apparatus disclosed which enables me to apply the great power contained in the hydrogen peroxide in an efficient manner. The exhaust gases from the decomposing hydrogen peroxide are highly oxidizing and have greater reactive powers in themselves which enables them to aid in the process of removing the solid material so that they enter into the combination and are not mere inert exhaust gases as in the prior art.

One object of the present invention is to provide an improved process and apparatus for removing solid material from a portion of a wall of a well.

Another object is to provide an improved process and apparatus for cutting pipe in two in a well.

Another object is to provide an improved process for perforating holes in a pipe in a well.

Another object is to provide an improved process and apparatus for drilling a well.

Another object is to provide suitable means for employing the power contained in hydrogen peroxide by releasing this power by contact with a

2

suitable hydrogen peroxide decomposition catalyst.

Numerous other objects and advantages will be apparent to those skilled in the art upon studying the accompanying specification claims and drawings.

Figure 1 is a cross sectional elevational view of a well containing an apparatus involving the present invention and in which well processes embodying the present invention are being carried out.

Figure 2 is a cross section view of the apparatus shown in Figure 1 taken along the line 2—2 looking in the direction indicated.

Figure 3 is a cross sectional elevational view of a modified form of a jet which may be substituted for the lower portion of the apparatus shown in Figure 1 when it is desired to perforate a hole in a pipe.

Figure 4 is a cross sectional elevation view of a third form of jet which may be substituted for the jet at the lower part of the apparatus shown in Figure 1 when it is desired to drill a hole in the bottom of a well.

Figure 5 is an elevational view of a modified form of the apparatus shown in Figure 1 in which means for preventing rotation are provided and in which the jet of Figure 3 is employed.

It is the purpose of this invention to provide process and means for using concentrated hydrogen peroxide as an agent for removing solid material from the wall of a well.

I have found that when used for such purposes that hydrogen peroxide possesses approximately the same amount of energy per pound as nitroglycerin and does not cost very much more per pound. It is impossible to release the energy of nitroglycerin at a controlled rate, as nitroglycerin detonates, whereas I have found that when hydrogen peroxide is contacted with a suitable hydrogen peroxide decomposition catalyst such as one selected from the group consisting of finely divided silver, finely divided platinum, the alkali metal permanganates, the alkaline earth metal permanganates and manganese dioxide, that the energy released can be controlled by supplying the hydrogen peroxide and controlling its contact with catalysts. For a given rate of flow of the hydrogen peroxide against the catalyst, a given amount of the catalyst is released in the form of high velocity gases consisting of steam and oxygen.

I prefer to employ the most concentrated forms of hydrogen peroxide available. At present it is possible to purchase 98 per cent hydrogen per-

oxide the other two per cent consisting of water and various well known materials which inhibit the decomposition of the hydrogen peroxide. I find however that valuable results can be obtained as long as the solution employed is at least 70 per cent by weight hydrogen peroxide. 70 per cent hydrogen peroxide can release about four thousand times its volume of hot steam and oxygen when suitably contacted with a catalyst and the 98 per cent hydrogen peroxide will produce even better results and hotter gases. The rate of decomposition is controlled closely by the rate of ejection of the hydrogen peroxide into a chamber containing the catalyst.

In Figure 1 a well generally designated as 6 contains a casing or pipe 7 the lower end 8 of which has been cut off by the operation of the apparatus shown by the removal of solid material of the pipe in the well at 9. 9 is an annular cut through the pipe 7 into the wall of the well 6. Suspended into space 11 in well 6 is a hydrogen peroxide cutting apparatus generally designated as 12. Apparatus 12 comprises a tank 13 having a filling plug 14 which tank is filled up to the dotted line 16 with concentrated hydrogen peroxide of at least 80 per cent by weight concentration. The tank 13 above surface 16 preferably filled with an inert gas such as nitrogen or carbon dioxide and this inert gas is preferably under high pressure to provide means for forcibly ejecting the hydrogen peroxide from the tank.

Tank 13 is suspended in the well 6 on a suitable suspension means such as cable 17, and in the form shown in Figure 1 it is preferred to provide a swivel connection 18 and 19 in order to allow rotation of tank 13 without twisting cable 17.

The hydrogen peroxide emerges from the bottom of tank 13 through an outlet conduit 21. The flow of hydrogen peroxide through conduit 21 is controlled by time valve 22 which is opened and closed by a clock 23. 22 is a shutoff valve and in place of clock 23 to make the device a time valve, I contemplate in some instances employing a remote control electric valve (not shown) in which a solenoid operates valve 22 and is controlled by an electric circuit including wires running to the surface of the ground, a source of power and a switch at the surface of the ground. I also contemplate valve 22 being controlled by a linkage mechanism having a portion projecting above tank 13 adjacent cable 17 and then dropping a go-devil, such as a section of pipe threaded on cable 17, (not shown) down the well to strike the linkage mechanism (not shown) to open valve 22.

It is preferred to also control the flow of the liquid in conduit 21 by a check valve 24 which allows flow outward through the conduit but prevents backward flow. While valve 24 is not absolutely essential and the device may be operated without the same in many instances, it is a desirable safety feature as the hydrogen peroxide decomposition process may cause hydrogen peroxide to tend to back up through pipe 21 and this decomposing hydrogen peroxide may contain fragments of catalytic material. Therefore these products of decomposition should not be allowed to enter tank 13.

After passing check valve 24 the hydrogen peroxide is discharged into a turbine rotor 25 provided with a central chamber 27 and one or more outwardly directed spiral passages 28. A portion of the wall of chamber 27 is lined with one of the suitable hydrogen peroxide decomposition catalysts listed above in the form of an insert

29. In order to simplify assembly insert 29 may be a portion of a cap member 31 which can be unscrewed in order to allow removal of head 26 from pipe 21. Pipe 21 is made in suitable sections fastened together at points such as 32 so that the parts disassemble.

As shown in Figure 1 the apparatus 12 is in place to commence the treatment of the wall 33 of well 6.

As shown in Figure 2 the passages 28 in head 26 are curved and spiral outwardly so that the emerging the jets 34 will not only have an outward force but a torque producing force rotation in the direction indicated by arrow 35 as in a reaction jet turbine. The catalyst cake or plate 29 in the center of cap 31 is directly in the path of flow of hydrogen peroxide out of outlet conduit 21.

When it is desired to employ a steady jet at a single point in place of the revolving jet or jets of Figure 1 then that portion of outlet conduit 21 below connection 32 is removed and replaced by lower outlet conduit 36 of Figure 3 which has a plug 37 in which is mounted a cake of catalytic material 38 and a jet 39 in a portion of the apparatus 41 which is directed at right angles from pipe 36.

When it is desired to drill with a downwardly directed jet, the device shown in Figure 4 is studied for the portions of the outlet conduit 21 below joint 32. The jet in Figure 4 consists of an upper pipe 42 and a lower pipe 43 containing an outlet jet 44. As one means of retaining the catalyst, the catalyst may be in the form of a ring 45 secured between pipes 42 and 43 and pipes 42 and 43 may be secured together by a coupling pipe 46.

When employing the directed jet 41 of Figure 3 it is often desirable to hold the jet at a single position. It is also often desirable to orient the direction of the jet. These two objects can be accomplished by providing tank 13' with the apparatus shown in Figure 5. Tank 13' not only has jet 41 but is controlled, rotated and oriented by a rigid rod or pipe 47 and 48 coupled by couplings 49. In this manner by surveying the device into the hole the direction of jet 41 is assured. Tank 13, and jet 41 can be prevented from rotation by providing spring spacing elements 51. Elements 51 center tank 13' in well 6 and space jet 41 a suitable distance from pipe 7 in order to perforate holes in the same or space jet 41 from wall 33 a suitable distance for the same purposes.

55 Springs 51 also act to prevent rotation occurring when the jet is turned on and thereby produce a more concentrated hole in the wall of the well.

Operation

60 Tank 13 is made of aluminum or other non-catalytic material and so are the portions of outlet conduit 21 down to the point where catalyst 29 is located. After that point it is immaterial whether the containing device is catalytic or non-catalytic and I prefer to make turbine head 26 and jet such as 43 of Figure 4 out of materials resistant to stress at high temperatures such as chrome steel alloys. It is not essential however that jets 26 and 43 be made of any particular material as they may be effective in directing the jet even though they are rapidly disintegrating in the process.

65 The device of Figure 1 is lowered into space 11 on the end of cable 17 and positioned by cable

17 at the depth desired. Clock 23 is set to allow sufficient time to do this. The operator then waits a sufficient length of time for clock 23 to open valve 22 and for the hydrogen peroxide to flow out outlet conduit 21 and complete the operation before removing the device from the well. The high pressure inert gas above surface 16 forces the hydrogen peroxide through open valve 22 and check valve 24 against catalyst 29. The hydrogen peroxide decomposition catalyst 29 decomposes the hydrogen peroxide and forms thereby about four thousand times its volume of hot steam and oxygen. The hot steam and oxygen rushes out jet 28 causing head 26 to rotate in the direction shown by arrow 35 in Figure 2. At the same time the outwardly directed jets cut, corrode and if inflammable materials are present they also burn their way through solid material and remove the same from a portion of the wall of the well bore. For example, if positioned at point 9 they would cut the lower part 8 from the upper part of pipe 7 as shown at 9.

If instead of passing through the turbine the jet is directed downwardly as shown in Figure 4 the jet will dislodge material from the bottom of the hole and drill the well making the same deeper.

If the jet is held substantially stationary as jet 41 in Figure 5 the jet may be directed to form a perforation in a pipe such as 7 or form a horizontal passage in the wall 33 of well 6 which passage increases the potential product of oil or other valuable material in the well. When employed in a well sand containing oil, the oxygen in the jet can burn the oil in the sand, heat the formation melting paraffin causing melting, spalling, expansion of gases in the formation aiding in the deepening of the horizontal hole.

While I have shown several preferred embodiments of my invention in the drawings and described the same in the specification, this has been done for purposes of illustration as the scope of the invention is described in the following claims.

While other substances act as hydrogen peroxide decomposition catalysts and may be used in practicing this invention, I prefer to use the catalysts listed in the claims as being more efficient. While I have shown in the drawings the use of a cake of catalyst obviously a supply of catalyst in liquid or powdered form could be dumped into the well before commencing operations, or fluid catalyst could be supplied simultaneously or intermittently as needed by employing the apparatus shown in my copending application Serial No. 69,212 filed January 4, 1949, entitled "Method and Apparatus for Well Drilling Operations Employing Hydrogen Peroxide" by substituting for the fuel 22 shown in tank 17 thereof a suitable hydrogen peroxide decomposition catalyst in fluid form. In such case the hydrogen peroxide would still be contacted with said catalyst as claimed herein.

Having described my invention, I claim:

1. The process of removing solid material from a portion of a wall of a well bore in the earth comprising positioning a supply of at least 70% by weight hydrogen peroxide adjacent the point of said removal in said bore hole, ejecting said hydrogen peroxide from said supply, contacting said ejected hydrogen peroxide with a hydrogen peroxide decomposition catalyst selected from the group consisting of finely divided silver, finely divided platinum, alkali metal and alkaline earth metal permanganates and manganese dioxide, 75

and directing the volume of steam and oxygen produced by said decomposition in a jet against said solid material to remove the same.

2. The process of removing solid material from a portion of a wall of a well bore in the earth comprising positioning a supply of at least 70% by weight hydrogen peroxide adjacent the point of said removal in said bore hole, ejecting said hydrogen peroxide from said supply, contacting said ejected hydrogen peroxide with a hydrogen peroxide decomposition catalyst, and directing the volume of steam and oxygen produced by said decomposition in a jet against said solid material to remove the same.

15 3. The process of removing solid material from a portion of a wall of a well bore in the earth comprising positioning a supply of at least 70% by weight hydrogen peroxide adjacent the point of said removal in said bore hole, contacting said hydrogen peroxide with a hydrogen peroxide decomposition catalyst, and directing the volume of steam and oxygen produced by said decomposition in a jet against said solid material to remove the same.

20 4. The process of removing solid material from a portion of a wall of a well bore in the earth comprising positioning a supply of at least 70% by weight hydrogen peroxide adjacent the point of said removal in said bore hole, ejecting said hydrogen peroxide from said supply, contacting said ejected hydrogen peroxide with a hydrogen peroxide decomposition catalyst, and directing the volume of steam and oxygen produced by said decomposition against said solid material to remove the same.

25 5. The process of removing solid material from a portion of a wall of a well bore in the earth comprising positioning a supply of at least 70% by weight hydrogen peroxide adjacent the point of said removal in said bore hole, contacting said hydrogen peroxide with a hydrogen peroxide decomposition catalyst, and directing the volume of steam and oxygen produced by said decomposition against said solid material to remove the same.

30 40 6. The process of severing a pipe in a well bore comprising positioning a supply of at least 70% by weight hydrogen peroxide in said bore hole, ejecting said hydrogen peroxide from said supply, contacting said ejected hydrogen peroxide with a hydrogen peroxide decomposition catalyst, and directing the volume of steam and oxygen produced by said decomposition in a plane normal to the longitudinal axis of said pipe to cut an annular groove through the pipe to sever the same.

35 45 7. The process of severing a pipe in a well bore comprising positioning a supply of at least 70% by weight hydrogen peroxide in said bore hole, contacting said hydrogen peroxide with a hydrogen peroxide decomposition catalyst, and directing the volume of steam and oxygen produced by said decomposition in a plane normal to the longitudinal axis of said pipe to cut an annular groove through the pipe to sever the same.

50 55 8. The process of perforating a pipe in a well bore comprising positioning a supply of at least 70% by weight hydrogen peroxide in said bore hole, ejecting said hydrogen peroxide from said supply, contacting said ejected hydrogen peroxide with a hydrogen peroxide decomposition catalyst, and directing the volume of steam and oxygen produced by said decomposition in a fixed jet normal to the surface of the pipe at the de-

sired point of perforation to make a perforation in said pipe at said point.

9. The process of perforating a pipe in a well bore comprising positioning a supply of at least 70% by weight hydrogen peroxide in said bore hole, contacting said hydrogen peroxide with a hydrogen peroxide decomposition catalyst, and directing the volume of steam and oxygen produced by said decomposition in a fixed jet normal to the surface of the pipe at the desired point of perforation to make a perforation in said pipe at said point. 10

10. The process of drilling a well bore hole comprising positioning a supply of at least 70% by weight hydrogen peroxide in said bore hole, 15 ejecting said hydrogen peroxide from said supply, contacting said ejected hydrogen peroxide with a hydrogen peroxide decomposition catalyst, and directing the volume of steam and oxygen produced by said decomposition in a jet downward against the bottom of said bore hole to deepen the same.

11. The process of drilling a well bore hole comprising positioning a supply of at least 70% by weight hydrogen peroxide in said bore hole, 20 contacting said hydrogen peroxide with a hydrogen peroxide decomposition catalyst, and directing the volume of steam and oxygen produced by said decomposition in a jet downward against the bottom of said bore hole to deepen the same.

12. Apparatus for producing a jet of hydrogen peroxide decomposition products comprising in combination a tank for said hydrogen peroxide, means to position said tank in a well, means to supply gas pressure to said tank to eject said hydrogen peroxide, an outlet conduit comprising a rotatable reaction jet turbine, a hydrogen peroxide decomposition catalyst secured in position in said outlet, a check valve in said outlet preventing back flow therethrough, a shutoff valve in said outlet, and means to open said shutoff valve comprising a clock control. 40

13. Apparatus for producing a jet of hydrogen peroxide decomposition products comprising in combination a tank for said hydrogen peroxide, 45 means to position said tank in a well, means to supply gas pressure to said tank to eject said hydrogen peroxide, an outlet conduit, a hydrogen peroxide decomposition catalyst secured in position in said outlet, a check valve in said outlet preventing back flow therethrough, a shutoff valve in said outlet, and means to open said shutoff valve comprising a clock control.

14. Apparatus for producing a jet of hydrogen peroxide decomposition products comprising in combination a tank for said hydrogen peroxide, means to position said tank in a well, means to supply gas pressure to said tank to eject said

hydrogen peroxide, an outlet conduit, a hydrogen peroxide decomposition catalyst secured in position in said outlet, a check valve in said outlet preventing back flow therethrough, a shutoff valve in said outlet, and means to open said shutoff valve.

15. Apparatus for producing a jet of hydrogen peroxide decomposition products comprising in combination a tank for said hydrogen peroxide, means to position said tank in a well, means to eject said hydrogen peroxide, an outlet conduit, a hydrogen peroxide decomposition catalyst secured in position in said outlet, a check valve in said outlet preventing back flow therethrough, a shutoff valve in said outlet, and means to open said shutoff valve.

16. Apparatus for producing a jet of hydrogen peroxide decomposition products comprising in combination a tank for said hydrogen peroxide, means to position said tank in a well, means to eject said hydrogen peroxide, an outlet conduit, a hydrogen peroxide decomposition catalyst secured in position in said outlet, a shutoff valve in said outlet, and means to open said shutoff valve.

17. The combination of claim 16 in which the discharge conduits comprise a rotatable reaction turbine.
